COMBINATION HANGER SUPPORT

John J. Derho, Mishawaka, Ind.

Application October 13, 1943, Serial No. 506,115

1 Claim. (Cl. 248—125)

My invention relates to emblems or the like, and includes among its objects and advantages the provision of an improved emblem having a combination hanger and standing support.

In the accompanying drawing:

Figure 1 is a perspective view of the rear face of an emblem in accordance with my invention.

Figure 2 is a sectional view along the line 2—2 of Figure 1.

Figure 3 is a face view of a hanger ring adapted to serve as a standing support, and

Figure 4 is a view similar to Figure 2 but illustrating the emblem in a standing position.

In the embodiment of the invention selected for illustration, I make use of an emblem 10 suitable to hang on a wall, stand on a table, shelf or the like. To support the emblem in its hanging or standing position, I provide a ring 12. This ring is bent from a piece of wire to the shape of a large loop 14, with a small eye 16 formed at one end of the wire. The plane of the loop 14 is arranged at an obtuse angle to the plane of the eye 16.

A screw 18 is passed through the eye 16 and threaded into the emblem 10 at a point where the emblem will hang straight when the ring is inserted over a supporting pin or the like. The head 20 of the screw is larger than the eye to press the latter against the rear face of the emblem.

Because of the angularity of the eye 16 with respect to the loop 14, the loop 14 serves as a prop positioned at an acute angle to the emblem when

the ring 12 is pivoted to the position of Figure 4. In this position, the ring terminates slightly short of the lower edge of the emblem, so that the emblem may rest on the support 22 at a suitable angle rearwardly and to the vertical when the ring is brought to rest on the support. When the loop 14 is hung on a wall pin, the emblem tilts forwardly to a suitable angle and its lower edge comes to rest on the face of the wall.

Without further elaboration, the foregoing will so fully explain my invention, that others may, by applying current knowledge, readily adapt the same for use under various conditions of service.

I claim:

An interchangeable support to suspend an object from either a vertical base or to support the same on a horizontal base, comprising a double circular looped wire supporting device, one circular loop of which is considerably larger than the other and bent at the point of connection between the loops to arrange said loops at an angle to each other, said wire being bent circularly in one direction to form the larger loop, and then bent circularly in the opposite direction to form the smaller loop, and the smaller loop adapted to be pivotally connected to the object to arrange the larger loop at an acute angle to the body, said larger loop when extending upwardly adapted to be connected with a vertical base, and when extending downwardly adapted to engage a horizontal base to support the object at an inclination from the horizontal base.

JOHN J. DERHO.
